UNITED STATES PATENT OFFICE.

CHARLES E. ROTH, OF NEW YORK, N. Y.

LIFTING-JACK.

No. 804,052.

Specification of Letters Patent.

Patented Nov. 7, 1905.

Application filed November 23, 1903. Renewed August 4, 1905. Serial No. 272,795.

To all whom it may concern:

Be it known that I, CHARLES E. ROTH, a citizen of the United States, residing at New York city, State of New York, have invented 5 new and useful Improvements in Lifting-Jacks, of which the following is a specification.

My invention relates to lifting-jacks of that type in which a lifting-screw is operated 10 by means of a gear-wheel and worm.

One of the principal objects of the invention is to provide a device of this character which shall be simple in construction and of few parts, which will not readily get out of order, and which may be quickly taken apart 15 for repairs or to replace worn or defective parts, and which may be readily reassembled without special tools.

Another object is to provide a strong and 20 durable device of the character referred to and one in which the lifting-screw shall be firmly mounted in a true vertical position to avoid torsional strains on the various parts of the structure.

25 A further object is to provide simple and efficient means for covering or housing the operative parts of the jack in order that dirt, grit, or any foreign substance may not find ready entrance to the working parts to interfere with the smooth and easy operation of 30 the mechanism. I have also provided a cover or housing for the operative mechanism which can be readily removed in order that access may be had to said mechanism 35 for the purpose of replacing worn or broken parts and for lubricating the bearings when found necessary.

The objects referred to are attained by 40 means of the construction illustrated in the accompanying drawings, in which—

Figure 1 is a view in vertical section of a 45 lifting-jack made in accordance with my invention. Fig. 2 is a top plan view and partial section of the same with the cap or cover of the housing removed to better illustrate the interior mechanism.

In order that the parts subjected to the greatest strains in use may have the required 50 strength, I have given such relative proportions to the different parts as will secure practical uniformity when constructed of the materials and of the relative dimensions set forth and hereinafter disclosed.

Referring to the accompanying drawings 55 for a more particular description of my invention, the numeral 1 designates the body

or standard of the jack. This body or standard is preferably made of cast-iron, the lower portion or base 2 being enlarged to provide a firm support for the jack and the body portion of the standard being hollow, as shown. The upper portion of the body is enlarged, as at 3, to provide a housing for the gear-wheel and worm.

A shouldered recess 4 is formed in the body 65 and supported within this recess is the annular ball-bearing ring or raceway 5, the upper surface of said ring having, preferably, two annular grooves 6, which provide raceways for the steel balls 7. The gear-wheel 8 may 70 be of case-hardened cast-iron and is provided with a depending bushing or boss 9, which fits smoothly within the upper portion of the standard to insure a true vertical alinement of the lifting-screw. A shoulder 10 is 75 formed on the gear-wheel below the cogs or threads 11, and firmly seated against said shoulder is a bearing-ring 12, which preferably has a smooth under face to rest upon the steel balls 7. The bearing-rings 5 and 12 80 may be secured in place by shrinking or otherwise. The bearing-ring 5 is preferably so constructed and attached within the body portion of the jack as to be readily removable and to be replaced when desired, while the 85 bearing-ring 12 is preferably shrunk or swaged against the laterally-extended shoulder 10 of the gear-wheel. A boss 13 is formed upon the upper end of the gear-wheel, and this boss fits within an opening 14 90 in the removable cap or cover 15. A shoulder 16 is provided immediately above the threaded portion of the gear-wheel, and the cap or cover 15 rests upon this shoulder.

It will be noted that the bushing 9 and the 95 boss 13 may be of substantially uniform diameter and that the shoulders 10 and 16 are preferably of substantially equal area, the object being to attain the greatest possible strength in line with the lifting-screw by 100 equalizing the bearing area of the gear-wheel by requisite proportions. Further, said shoulder 16 also constitutes an extended bearing-surface whereby the gear-wheel is prevented from moving upward from any 105 cause. The crucible-steel lifting-screw 17 has a comparatively long screw-threaded bearing within the gear-wheel, owing to the extended bushing 9 and the boss 13, and is thus firmly seated in a true vertical line relatively to the body or support. This is a 110 matter of considerable importance in a de-

vice of this character, as any torsional or side-
wise strain would have a tendency to injure
or crush some of the parts under the great
weight being raised. The head 18 rests upon
5 the upper end 18^x of the lifting-screw 17, a
set screw or pin 19 being used to hold the top
18^x in place. The crucible-steel worm 20
has one end 21 of its shaft journaled in a boss
or enlargement 22, formed inside the body 1,
10 and the other bearing for the worm-shaft is
formed in a steel bushing 23, and said bush-
ing is fitted into a threaded enlargement 24,
formed inside the body 1. A pin or screw 25
holds the bushing 23 in place in its bearing.
15 A handle 26, which may be of the ratchet
type, is secured in any suitable manner to
the outer end of the worm-shaft. The top
or cover 15 may be held in place by screws
which pass through said top or cover and
20 into the holes 27, formed in the top of the
body portion.

It will be noted that when the head 18 is
secured in place upon the end 18^x of the lift-
ing-screw 17 the flat lower end of the head 18
25 extends beyond the shoulder 14 on the gear-
wheel 8 and covers the joint between the boss
13 and the opening in the top of the cover-
plate 15, and thus serves to keep grit or dirt
from gaining access to the working parts of
30 the jack when not in use.

From the foregoing it will be obvious that
my lifting-jack is comparatively simple in
construction, is composed of few parts, that
the operative mechanism is completely cov-
35 ered and housed in to protect it from injury,
and that access may be readily gained to the
parts for repairs, that the lifting-screw is
seated in a long bearing to hold it in vertical
position to prevent sidewise strains, and that
40 the relative proportions of the parts are such
as to secure substantially uniform strength
to the jack in its various parts.

Having thus fully described my invention,
what I claim, and desire to secure by Letters
45 Patent, is—

1. A lifting-jack comprising a hollow body
portion, a gear-wheel having a bushing de-
pending from one end thereof and a boss ex-
tending from the opposite end thereof, said
50 bushing being seated in a bearing in the body

portion, a ball-bearing for the gear-wheel, a
threaded lifting-screw passing through the
gear-wheel and bushing, and a removable
cover-plate for inclosing the operative parts
of the jack, said cover-plate having an open-
55 ing through which the said boss extends, and
the upper faces of said boss and plate being
flush.

2. A lifting-jack comprising a hollow body
portion, provided with an interior shoul-
dered recess, a ball-raceway in the form of a
ring seated in the recess and provided with
ball-grooves, balls in the grooves, a smooth-
surfaced bearing-ring resting upon the balls,
a gear-wheel resting upon the bearing-ring, a
60 bushing extending from the gear-wheel and
seated in a bearing in the body, a boss ex-
tending from the upper end of the bushing, a
lifting-screw, a worm for revolving the gear-
wheel and lifting the screw, and a removable
65 cover-plate for inclosing the operative parts
of the jack, said cover-plate having an open-
ing through which said boss extends, the up-
70 per surfaces of said boss and plate lying in
the same plane.

3. A lifting-jack comprising a hollow body
portion having an interior shouldered recess,
a ball-bearing ring seated in said recess and
provided with ball-raceways, balls in the
raceways, a gear-wheel provided with a de-
75 pending bushing journaled in the hollow body
portion, a bearing-ring secured to a shoulder
on the gear-wheel and resting upon the balls,
a worm-shaft journaled at one end in the
body portion, a threaded bushing in which 80
the opposite end of the worm-shaft is jour-
naled, and a removable cover-plate for cover-
ing the operative portions of the jack, said
cover-plate having an opening which fits
85 over a boss on the upper end of the bushing
and the plate and boss having flush upper
surfaces.

In testimony whereof I have signed my
name to this specification in the presence of
two subscribing witnesses.

CHARLES E. ROTH.
